UNITED STATES PATENT OFFICE.

BENJAMIN C. HASKELL, OF ARLINGTON, MASSACHUSETTS.

DESIGN FOR A CHAMBER-SLIPPER SOLE.

SPECIFICATION forming part of Design No. 29,692, dated November 15, 1898.

Application filed August 30, 1898. Serial No. 689,874. Term of patent 14 years.

To all whom it may concern:

Be it known that I, BENJAMIN C. HASKELL, of Arlington Heights, in the county of Middlesex and State of Massachusetts, have invented and produced a certain new and original Design for Chamber Slipper Soles, of which the following is a description.

The leading feature of my design consists in an insole having a stepped appearance at its edge formed by the textile fabric, which is readily distinguishable in appearance from the felted material of the lining, a shoulder being formed about midway of the side of the lining, a vertical wall extending from said shoulder downward to the point of meeting with a horizontal portion of the sole, and a rounded surface being formed below said horizontal portion.

In the drawings, Figure 1 is a perspective view of a chamber-slipper sole, showing my new design. Fig. 2 is a bottom or inverted plan view of the same. Fig. 3 is a cross-sectional view of the same.

In said drawings, *a* represents a vertical wall of textile fabric extending substantially half-way up the side of the edge of the lining *g*.

At *b* the textile fabric is shown as rounded and then extending horizontally inward until it meets the vertical wall *a* at *c*.

The configuration or shape of the sole in 30 its entirety, including the vertical wall, the rounded portion, and the horizontal portion connecting these two, and the surface ornamentation due to the contrast between the woven fabric and the felted fabric, the said 35 woven fabric having the particular shape described, constitute particular features of this new design.

Having described my design, I declare that what I claim as new and as of my invention is— 40

The design for a chamber-slipper sole as herein shown and described.

In testimony whereof I have signed my name to this specification, in the presence of two subscribing witnesses, this 23d day of 45 August, A. D. 1898.

BENJAMIN C. HASKELL.
